[57] **CLAIM**

The ornamental design for a flat car for a track mounted linear motor driven conveyance device for conveying small things, as shown and described.

DESCRIPTION

FIG. 1 is a bottom, front and side perspective view of a flat car for a track mounted linear motor driven conveyance device for conveying small things showing my new design;

FIG. 2 is a front elevation view thereof;

FIG. 3 is a rear elevation view thereof;

FIG. 4 is a top plan view thereof;

FIG. 5 is a bottom view thereof;

FIG. 6 is a right side elevation view thereof; and,

FIG. 7 is a left side elevation view thereof.

FIG.1

FIG.2

FIG.3

FIG.4

FIG.5

FIG.6

FIG.7
